UNITED STATES PATENT OFFICE.

CYRUS S. DEAN, OF FORT ERIE, CANADA, ASSIGNOR TO ALBERT D. JAMIESON, OF BUFFALO, NEW YORK

WATER-WHEEL.

No. 822,927.

Specification of Letters Patent.

Patented June 12, 1906.

Application filed April 11, 1905, Serial No. 255,016.

To all whom it may concern:

Be it known that I, CYRUS S. DEAN, a subject of the King of Great Britain, residing at Fort Erie, county of Welland, Province of Ontario, Canada, have invented certain new and useful Improvements in Water-Wheels, of which the following is a specification.

My invention relates to water-wheels, and more particularly to means for raising and lowering them from and into the water.

The object of the present invention is the provision of improved and novel means for raising water-wheels from the water and for lowering them into the water when desired, and in this connection I aim to provide an improved and superior construction to those heretofore employed by the provision of a water-wheel frame carrying the water-wheel and arranged to be lifted bodily with the water wheel or wheels from the water, and to carry out my invention in this respect the water-wheel frame is hinged or pivotally mounted on the same axis as that of the transmitting-shaft to take off the power derived from the water-wheel or water-wheels, thereby enabling a very simple and effective form of gearing to be used, rendering the construction compact, strong, efficient, and durable and providing in general a construction superior to those heretofore known to the art.

To accomplish the raising and lowering of the water-wheel frame, I provide flexible means suitably operated by hand or a motor in connection with an improved arc-shaped guide and support for said flexible means, whereby the use of extra pulleys or sheaves is obviated and the pull of the flexible means on the water-wheel frame is in a direction substantially at right angles thereto at the most advantageous point, thus facilitating raising and lowering of the water-wheel frame with the least possible expenditure of power and minimum strain on the parts. In connection with the flexible operating means aforesaid an improved counterbalancing device is provided to enable the water-wheel frame and water wheel or wheels to be raised and lowered by the use of a minimum amount of power.

Various types of water-wheels can be employed; but the improved feathering water-wheel which I have invented is especially adapted for use in this connection by reason

of its simplicity, strength, lightness, and manner of operation.

Having thus generally set forth the objects and nature of my invention, reference is to be had to the following specification for the details of construction of that form of the invention which at the present time constitutes the most complete embodiment of my ideas, which I have produced, and the appended claims set forth the scope of the invention.

In the accompanying drawings, Figure 1 is a side elevation of the complete device; Fig. 2, a plan view in section on line 2-2 of Fig. 1; Fig. 3, an enlarged plan view, with the top frame removed, of the water-wheels; Fig. 4, a perspective detail of one of the blades or paddles of the water-wheel; Fig. 5, a detail elevation, partly in section, of a modified form of water-wheel which may be used in my invention; Fig. 6, a top view thereof.

Situated at the side of the mill-race, on some suitable foundation, is a frame 1, consisting of upright and horizontal members, preferably of tubular construction. One of the horizontal members 1^a of the frame 1, Fig. 2, constitutes the pivot bar or shaft for the water-wheel frame 2, which consists of 8^a parallel horizontal plates or bars 2^a at the top and bottom of the frame and connected by pillars 2^b and cross-plates 2^c connecting the bars or plates 2^a. (See Fig. 2.) Rising from certain of the cross plates or bars 2^c are pillars 3 and 4, which are connected by bars 5 and 6, (see Fig. 2,) pivoted or hinged on the bar 1^a by the sleeve 7. This construction gives great strength and prevents straining of the water-wheel frame 2^a, 2^b, and 2^c.

By preference two water-wheels 8 and 9 in all respects similar are employed. These water-wheels have a central shaft 10 journaled in the cross-pieces 2^c of the water-wheel frame, and to these shafts are rigidly secured upper and lower wheel-like frames 11 and 12, whose peripheral portions are connected and braced by vertical bolts 13, located at quadrant distances apart, and on these bolts the paddles 14 (shown in detail in Fig. 4) are pivoted. The paddles or blades 14 are of sheet metal or boiler-plate and provided with flanged edges 15, which give them great strength with great lightness. The bolts 13 pass loosely through openings 16 in the flanges 15, and the blades or paddles 14

are spaced from the heads or frames 11 and 12 by washers 17. To each paddle 14 is secured an arc-shaped plate 18, having an arc-shaped slot 19 therein, and the flanges 15 afford a convenient surface for the attachment, by rivets 20, of the ends of these plates 18. Pins 21 on the spokes of the lower frames or heads 12 project into the slots 19 and limit the outward play or swing of the paddles or blades, as clearly shown in Fig. 3. The paddles or blades 14 when swung inwardly by the force of the water, as shown in Figs. 1 and 3, abut upright rods or bolts 22; but these could be dispensed with, and the free ends of the paddles or blades might be arranged to abut the shaft 10. To direct the water to the water-wheels, it being understood that they turn toward each other, as indicated by the arrow in Fig. 3, the plates 23 are provided, these being shown in dotted lines in Fig. 1, and said plates are suitably secured to the frame 2 and converge toward each other. They may be conveniently constructed of sheet metal or boiler-plate with flanged edges. To the upper ends of the shaft 10 are secured bevel-gears 24, which mesh with bevel-gears 25, secured on a shaft 26, mounted in pillow-blocks 27, rising from certain of the cross-plates 2^c. The inner end of shaft 26 carries a bevel-gear 28, which meshes with a bevel-gear 29, fast on a sleeve 30, which is loose on the rod or bar 1^a and has secured thereto a belt-wheel 30^a, from which power may be taken off to any device to be driven. In Figs. 5 and 6 I have shown another form of water-wheel which can be used in place of the wheel heretofore described. In these figures the shaft 10^a is substituted for the shaft 10, and said shaft 10^a is provided with a semispherical shell or cup 32, having four slots 33 made upwardly therein from its flanged edge 34. A continuation of the shaft 10^a is shown at 10^b, and this shaft-section is formed integral with a lower semispherical or cup-shaped part 35, having a flange 36 secured to flange 34 by bolts 37, and the cup 35 has four slots 38 arranged at quadrant distances apart and constituting downward continuations of the respective slots 33. It will be understood that as many blades or paddles can be used as found desirable; but, as previously, I prefer to employ but four, as shown at 39. The blades or paddles are arranged in pairs, which are connected in diametrically opposite positions by obtuse-angled bars 40, suitably secured to the blades at 41. The bars 40 are adapted to play in the slots 33 38 by an up-and-down movement, as will be explained presently. The bars 40 are formed with sectoral parts 42, 42^a, and 42^b. The upper part 42 conforms to the interior of the cup 32 and bears thereagainst, and the parts 42^a and 42^b conform to the lower cup 35 and turn therein and are separated by a cut-out portion.

The foregoing description applies especially to the pair of blades and connecting parts shown in elevation in Fig. 5. The pair of blades and connecting parts 42, 42^a, and 42^b of the pair of blades located at right angles to those shown in elevation in Fig. 5 and shown in Fig. 6 are of the same construction, but the positions of the parts 42, 42^a, and 42^b are reversed—i. e., part 42 turns in the cup 35 and the parts 42^a and 42^b turn in the cup 32, while the notch or cut-out portion between the parts 42^a and 42^b is uppermost instead of lowermost. Each bar 40 has a lug 43 on its upper edge.

The numeral 44 represents a wheel provided with a beveled face and having four notches 45 located at quadrant distances apart and arranged to receive the lugs 43. It will be understood that the wheel 44 is secured to a short or stub shaft 46, which is turned idly by the rotation of the water-wheel, causing the blade in the water to engage and turn the wheel 44, and that said shaft 46 is not positively driven. In Fig. 5 the right-hand blade 39 is in position to be moved by the water, while the left-hand blade is out of the water. As the blades move in the water and the shaft 10^a 10^b turns, the blades out of the water come in contact with the beveled surface of wheel 44 and are gradually depressed, the other blade being correspondingly raised until it finally leaves the water at the proper point. The blades successively dip and raise or feather.

In the form of water-wheel shown in Fig. 3 as the blade drags it is in line with the flow, but as the wheel rotates it is swung around and receives the force of the water on its face while it is in contact with the stop or rod 22, and afterward passes to feathering position.

Rigidly secured to the respective pillars 3 are parallel upright arc or segment shaped channel irons or bars 50 and 51. Lying in each channel-bar are a cable 52 and a sprocket-chain 53, which are securely anchored to the columns or pillars 3 and for the balance of their length lying loosely on said channel-bars.

It will be understood that either the cable or the chain could be dispensed with; but I prefer to use both, so that in case of breaking, stretching, or injury to one the other will be present and no accident or damage to the device occur. Journaled in suitable bearings on frame 1 is a shaft 54, on which sprocket-wheels 55 and sheaves 56 are rigidly secured. The cables 52 pass over the sheaves, and the sprocket-chains 53 engage with the teeth of the sprocket-wheels. On shaft 54 is a gear 57, which can be turned by a pinion 58, operated by a crank 59; but instead of using hand-power a suitable motor, such as an electric motor, can be used for turning the shaft 54, and it will be found convenient in some instances to use a storage

battery to operate an electric motor for this purpose, the storage battery being charged by any suitable electric generator driven by the water-wheel. Sliding vertically on vertical guides 60 is a counterbalancing-box 61, which can be filled with water or weights of any kind, or stones, to the desired extent to properly counterbalance the weight of the water-wheel frame, water-wheels, and other parts carried by the water-wheel frame. Carried by the box 61 is a shaft on which are sheaves 62 and sheaves 63, under which the cables and sprocket-chains pass and then lead upwardly to the frame, where they are fastened at 64.

It will be understood that the use of the arc-shaped bars 50 and 51, connected to suitable points of the water-wheel frame, in connection with a flexible chain or cable secured to the water-wheel frame and lying loose on the arc-shaped bar, enables the pull to be made substantially at right angles to the water-wheel frame, thus dispensing with the use of extra sheaves or pulleys and enabling the water-wheel frame and water-wheel to be raised and lowered with great ease and minimum strain on the parts, and this construction also obviates the necessity for the use of bulky parts and permits hinging or pivoting of the frame without increasing the power necessary to raise and lower the frame and water-wheels from and into the water, for it will be understood that not only are the water-wheels raised from the water, but the entire water-wheel framework and all parts carried thereby are raised on the shaft 1° as a pivot, and by using this construction the taking off of the power obtained from the water-wheels requires only a simple and yet very satisfactory gearing.

Having thus described my invention, what I claim as new, and desire to secure by Letters Patent, is—

1. In a water-wheel raising and lowering mechanism, the combination with a water-wheel frame and means for hinging or pivoting said frame so that it may be bodily lowered into the water or raised therefrom, of an arc-shaped bar secured to the water-wheel frame and movable therewith, and a flexible

connection connected to the water-wheel frame and lying on the arc-shaped bar aforesaid and adapted to be pulled or drawn upon to raise or lower the water-wheel frame.

2. In a water-wheel raising and lowering mechanism, the combination with a water-wheel frame and means for hinging or pivoting said frame so that it may be bodily lowered into the water or raised therefrom, of an arc-shaped bar secured to the water-wheel frame and movable therewith and lying in the arc of a circle whose center is the pivotal point of the frame, a flexible connection secured to the water-wheel frame and lying loosely on the arc-shaped bar, and means for drawing up or letting out said flexible connection to raise or lower the water-wheel frame.

3. In a water-wheel raising and lowering mechanism, the combination with a water-wheel frame and means for hinging or pivoting said frame so that it may be bodily lowered into the water or raised therefrom, of an arc-shaped bar secured to the water-wheel frame and movable therewith, a flexible connection secured to the water-wheel frame and lying loosely on the arc-shaped bar, and a counterbalance coöperating with a free portion of said flexible connection.

4. In a water-wheel raising and lowering mechanism, the combination with a water-wheel frame and means for hinging or pivoting said frame so that it may be bodily lowered into the water or raised therefrom, of an arc-shaped bar secured to the water-wheel frame and movable therewith, a flexible connection secured to the water-wheel frame and lying loosely on the arc-shaped bar, a counterbalance coöperating with a free portion of said flexible connection, and mechanism for drawing up or letting out said flexible connection to raise or lower the water-wheel frame, said mechanism coöperating with the flexible connection between the counterweight and the arc-shaped bar.

In testimony whereof I hereunto affix my signature in presence of two witnesses.

CYRUS S. DEAN.
